UNITED STATES PATENT OFFICE.

ALFRED M. LANE, OF ST. LOUIS, MISSOURI, ASSIGNOR TO MONARCH METAL WEATHER STRIP COMPANY, OF ST. LOUIS, MISSOURI, A CORPORATION OF MISSOURI.

FRUIT-TRAY.

1,244,617.

Specification of Letters Patent.

Patented Oct. 30, 1917.

Application filed May 9, 1917. Serial No. 167,551.

To all whom it may concern:

Be it known that I, ALFRED M. LANE, a citizen of the United States, and a resident of the city of St. Louis and State of Missouri, have invented a new and useful Improvement in Fruit-Trays, of which the following is a specification.

This invention relates to sheet metal ware, and particularly to trays for drying fruit.

10 The objects of the invention are strength and lightness of construction, coupled with ease of replacement of parts subject to wear and rust. A further object is convenience in handling the tray and in stacking up 15 trays one on another.

The invention consists in the details of construction hereinafter described, reference being had to the accompanying drawings which illustrate the invention in a preferred 20 form.

What is claimed as the invention appears from the appended claims.

In the drawings, wherein the same reference characters designate the same parts in 25 the several views,

Figure 1 is an isometric view of a fruit drying tray embodying the invention;

Fig. 2 is a bottom view of one corner of the tray drawn to a large scale, a portion of 30 the figure being in section along the middle of the base frame to disclose the screen clamp rods and corner brace; and

Fig. 3 is a transverse section through the edge portion of the tray, showing the corner 35 brace in elevation.

The tray consists of sheet metal side walls 11 and a woven wire bottom 12. The side walls slope outwardly and have a ledge 13 projecting outwardly part way up from the 40 bottom of the tray and extending around its four sides. The top edges of the sides are curled around a wire 14 which secures them together at the corners. The bottom edges of the sides are bent out and down and in to 45 form a hollow base 15. The wire bottom 12 is bent around the outer edges of hollow frame members 16 which are mitered together at their corners and are inclosed by

the base portion 15 of the sides. The outer edges of the frame members 16 are concave, 50 forming a groove around the frame, and the edges of the wire bottom are clamped in the bottom of the groove by rods 17 made of wood or other suitable material, which are held between the frame members and hollow 55 base 15. Angle braces 18 are screwed, riveted or otherwise secured to the frame members at the corners of the tray, and the screws 19 which secure them in place pass through the bottom flanges of the hollow 60 base portions 15 of the side walls and fasten them to the frames.

The base of the tray is slightly smaller than the vertical position of the side walls, so the trays may be stacked up with the base 65 of one resting upon the ledge 13 of the tray beneath. The ledges 13 also provide a convenient means for lifting the tray and for supporting it in a rack.

I claim the following as my invention: 70

1. A tray having side walls provided with ledges integral therewith, and an openwork bottom, the lower edges of the side walls inclosing said bottom and forming a base the overall dimensions of said base being small 75 enough to permit it to enter a like tray and rest on the ledges thereof.

2. A tray having outwardly sloping side walls provided with ledges integral therewith located partway up said sides, and an 80 openwork bottom, the lower edges of the side walls supporting said bottom and forming a base whose dimensions are slightly less than those of the top opening of said tray, whereby when a number of trays are nested, 85 the base of each tray rests on the ledges of the tray beneath.

3. A tray having side walls, and an openwork bottom, a frame for said bottom, said frame having a groove around its outer 90 edge, and means in said groove for securing said openwork bottom to said frame, the lower edges of the side walls being formed in a hollow rib inclosing said frame and clamping said securing means and said bottom and forming a base for the tray. 95

4. A tray having side walls, and an open-work bottom, a frame for said bottom, said frame having a groove around its outer edge, means in said groove for securing said open-work bottom to said frame, the lower edges of the side walls being formed in a hollow rib inclosing said frame and clamping said

securing means and said bottom and forming a base for the tray, and braces in the corners of said hollow rib secured to said frame and to said side walls.

Signed at St. Louis, Missouri, this seventh day of May, 1917.

ALFRED M. LANE.
